UNITED STATES PATENT OFFICE.

OSCAR COBB, OF CHICAGO, ILLINOIS.

REVOLVING DOOR.

SPECIFICATION forming part of Letters Patent No. 729,548, dated June 2, 1903.

Application filed March 21, 1900. Serial No. 9,482. (No model.)

To all whom it may concern:

Be it known that I, OSCAR COBB, of Chicago, in the State of Illinois, have invented certain new and useful Improvements in Revolving 5 Doors, of which the following is a specification.

This invention relates to revolving doors mounted at angles to one another on a central pivotal upright post and used in conjunction with entrances or exits having arc-shaped sides designed to keep the doorway constantly closed against air-currents while permitting persons to make entrance into or exit from the inclosure; and the objects of my improvements are, first, to provide an arrangement of the doors for increasing the walking-space between the doors without increasing the width of the doorway; second, to provide a hinge connection of some of the doors with 10 the pivotal upright, whereby the relation of the doors as to each other may be varied for certain purposes; third, to provide means for locking the hinge connection when the doors are in normal position for use; fourth, to provide means for adjusting the pivotal upright on ball-bearings and keeping out dust from the bearings; fifth, to provide means for adjusting the center-pin of the pivotal upright so that the pin can be easily thrown out of 15 connection with the floor and ceiling of the doorway for disconnecting the pivotal upright therefrom; sixth, to provide means for suspending the doors to the ceiling of the doorway when the center-pin is thrown, so that 20 the doors can be moved to one side of the doorway; seventh, to provide wedge-shaped doors having their thickest portion adjacent to the pivotal upright, with a view of disposing of the greater part of the stock and weight 25 of the doors toward the center of the structure and correspondingly lightening the outer portions; eighth, to provide means for preventing liability of injury to persons from being caught between the doors and the side 30 of the door-frame, and, ninth, to provide means for locking the doors to the floor of the entrance in any position. I attain these objects by the means illustrated in the accompanying drawings, in which—

50 Figure 1 is a fragmentary side elevation of the lower part of a set of revolving doors containing my invention. Fig. 2 is a horizontal

section taken at about the plane of the middle of the doors. Fig. 3 is a detail showing a vertical section on the line 3 3 of Fig. 2, extended through a fragment of the floor of the entrance. Fig. 4 is a detail showing, in elevation, a fragment of one of the doors at the upper edge thereof and the means for suspending the doors to the ceiling of the entrance and shifting them to one side, and also a longitudinal vertical section showing a fragment of the ceiling on the line 4 4 of Fig. 6 through one of the points of the connection of the suspending means therewith. Fig. 5 is a detail, partly in section and partly in elevation, showing a fragment of the door and the suspending means viewed at right angles to the view shown in Fig. 4. Fig. 6 is a detail showing in plan view a transverse fragment of the ceiling of the doorway. Figs. 7 and 8 are details showing, respectively, an enlarged side elevation and a plan or top view of a detached part. Figs. 9 and 10 are details showing, respectively, an enlarged front 75 and a side elevation of a part as applied to the door. Figs. 11 and 12 are details showing in elevation detached parts of the part shown in Figs. 9 and 10. Fig. 13 is an elevation of an entrance-way and the doors therein complete. Fig. 14 is a diagrammatic plan, partly in section, showing a fragment of the inclosure walls, the arc-shaped sides of the entrance, the doors therein, and the relative position of other features. Fig. 15 is a diagrammatic view showing the position of the doors when folded together. The normal relation of the doors so folded to the doorway is along or through, not transversely to, the same. Fig. 16 is a diagrammatic view showing a modification, the doors being folded. Fig. 17 is an enlarged diagrammatic view showing the taper of one of the doors, its position with relation to the pivotal center of the upright shown by dotted lines, and the 80 means for making the doors flexible for certain purposes.

In the drawings, A designates the doors, and B the pivotal upright.

C is the floor of the doorway; C', the ceiling, and C² the arc-shaped sides of the inclosure.

The upright is pivoted to the floor and ceiling by pins a, centrally located in the upright

and entering suitable holes in the floor and ceiling in the middle of the doorway.

For the purpose of increasing the walking-space between the doors I connect their sides to the sides of the upright, as shown in Fig. 2, so that they are not extended in the line of the pivotal center, but are placed to one side thereof.

As shown in Figs. 14 and 17, neither side of the angles formed by the adjoining faces of the doors is in line with the axis of rotation, and the vertexes of all said angles have like relation to said axis. The faces of the doors are at considerable distance from radial lines drawn parallel therewith, those nearest being off more than half the thickness of the doors. The arc-shaped sides of the easement are concentric to the axis of rotation; but the doors and both sides of the angles inclosing the walking-space between them are eccentric thereto, all the doors and angles having the same relation to the axis of rotation and arc-shaped easement. By this arrangement of the parts a considerable advantage is given to the walking-space embraced by the angles between the doors in length or in the direction through the way without increasing its width. I distinguish this construction from revolving-door structures in which a series of radial doors or wings are united at a central junction-line, so as to permit of fixing them in planes either parallel or at any required angle with respect to each other. In such radial-door structures the sides or lines of the doors facing toward the junction-line are not eccentric to the axis or easement, but in or on radial lines, and both sides of all angles between the wings are not off the center-line nor required to be so, nor is it necessary that the vertexes of all such angles should have the same relation to the rotation. Such structures are not designed to increase the walking-space lengthwise between the doors and do not practically secure that result.

For the purpose of varying the normal relation of the doors, as when in use, I connect but two, or in some cases but one, of the doors, rigidly or permanently with the upright and hinge the other doors to the ones having the permanent connection. Fig. 2 shows two of the doors connected permanently to opposite sides of the upright by means of spikes *b b*, the other doors being connected by hinges *c c* to these and having no fixed connection to the upright. By this means the hinged doors can be folded upon the others to the position shown in Fig. 15 and extended through the doorway. By attaching one only of the doors rigidly to the upright and using three of the hinge connections *c* the doors may be folded, as shown in Fig. 16.

For the purpose of locking the hinged doors in their normal relation for use I provide a hinged lock or piece *D*, which is adapted to be attached to a rigidly-connected door and to engage a striking-piece *D*, Figs.

7 and 8, adapted to a door hinged thereto. One member *d* of the piece *D* carries a swiveling eccentric cam *d'*, provided with a handle or lever *d²*, and the piece *D'* has a catch *d³* with which the cam is adapted to engage when the member *d* is thrown over against the piece *D'*, and the lever is thrown over to the position seen in the drawings. The lock 75 is released when the lever is reversed and the member *d* can then be turned back, so as to allow the hinged door to turn on its hinges *c* and fold upon the relatively fixed door to which it is so connected, as illustrated by 80 dotted lines in Fig. 2.

The upright is carried on ball-bearings, which comprise a metallic plate *E* set in the floor of the doorway, a plate *E'* fitting loosely in a recess in plate *E*, the adjacent faces of 85 said two plates being provided with a circular recess or depression forming a ball-race *e* and a set of balls in the ball-race. The upright has rigid connection with the plate *E'*, so that when turned the upright will turn 90 said plate and be carried around on the balls traveling in the ball-race. A sheet *e'* of rubber, sole-leather, or similar material is connected around the upright near the bottom and adapted to bear upon the floor of the 95 doorway outside of the plate *E'* for excluding dust from the ball-bearings.

For the purpose of detaching the upright from the floor and ceiling and removing it or shifting its position in the doorway the pins 100 *a* are set so as to slide in a sleeve or perforated plate *a'*, attached to the ends of the uprights and connected to links *a²*, each extending partly through a central bore of the upright and attaching to a swivel-plate *a³*, located in a chamber or recess in the upright and provided with a projection *a⁴*, adapted to receive a key for swiveling the plate, and thereby pulling the links toward the swivel-plate and drawing the pins out of engagement with the holes in the floor and ceiling. The links will also serve the purpose of projecting the pins *a* from the ends of the upright on a reverse movement of the swivel-plate when replacing the doors in the doorway for use. The chamber or recess in the upright for the swivel-plate is covered by one of the hinged doors *A*, so as to be accessible when the door is folded, as before described, upon the door to which it is hinged. The 115 pin *a* and the hole in the sleeve *a'* and plate *E'* are square to cause the plate *E'* to revolve with the upright.

For the purpose of suspending the doors to the ceiling of the doorway and sliding them 120 to one side thereof I provide two parallel slide-ways *F* in the ceiling, which are extended from one side of the doorway toward and somewhat beyond the point of the pivotal connection of the upright part, their position being illustrated in Fig. 14. Said slide-ways 125 preferably comprise a long metallic box *F* with a slot in its under side and having screw-holes through its upper side and through

flanges on its lower side in which screws f' are applied for securing it in a suitable recess in the wainscot of the ceiling. A sliding piece F' is fitted to slide within the slideway and has a slot g in the under side with flanges f'' depending in the slot f . G is a threaded bolt with one end pivoted to the door near its upper edge, so as to swing parallel with the door. G' is a sleeve internally threaded at its opposite ends, and G^2 is a threaded bolt provided with a T-head. The threads of the bolts and sleeve are oppositely inclined, so that rotation of the sleeve will draw the bolts together or move them apart in accordance with the direction of rotation. When the T-head is presented edgewise, it can be passed into the slot g and then the bolt can be turned a quarter, so as to bring the head across the slot, and in this position rotation of the sleeve in the proper direction will cause the head to bear upon the sliding piece, and thereby the doors may be suspended from the ceiling. The suspending means is used in connection with two of the doors on opposite sides of the upright in the position illustrated at G^2 , Figs. 14 and 15, so that when the doors are folded together and extended through the doorway and transversely to the slideways they may be suspended from a sliding piece in each of the slideways and moved over to one side of the doorway, where they can be secured to the floor and left until required for further use. I prefer to rest the suspending-bolt G^2 on a pin or hook g' , Fig. 4, when not in use. For the purpose of disposing of the greater amount of stock and weight toward the center I make the doors thickest at the inner portion next to the upright and gradually reduce the thickness toward the opposite or outer portion, as illustrated in Fig. 17, which shows the thickness of the outer portion reduced to nearly one-half as compared with that of the opposite portion. By this means

adapted to the flexible joint of the rod and to hold it off from the door, so that the tension of the spring will tend to hold the outer part of the door in normal position for use, but will yield and permit it to bend back in the event of its meeting substantial obstruction or unusual resistance in the way when the revolving structure is in motion.

For the purpose of locking the doors to the floor of the entrance in any position I employ a surface bolt having an eccentric elastic foot-piece for contact with the floor and means for pressing the foot-piece to lock it in place there. Such bolt as invented by me is illustrated in Figs. 9, 10, 11, and 12, and comprises a plate J , provided with screw-holes and inclined teeth j , a barrel j' for the bolt K , which has a foot-piece k , pivoted thereto through an elongated opening k' , eccentric to the curve of the bottom of the foot-piece, and a lever or handle K' , provided with inclined teeth k'' on one side. The bolt K is provided with a longitudinal groove L , having a transverse extension m at the lower end and a similar extension m' at the upper end, in conjunction with the reduced end m^2 of the bolt. The handle K' is provided with a hole adapted to fit on the reduced end m^2 and is secured thereon by riveting, and it is free to revolve thereon through a quarter of a revolution. A lug n on the handle works in the slot m' and operates as a stop against the ends of the slot to prevent further revolution. A stop-pin n' works in the slots L to permit the bolt to be raised and lowered and to prevent rotation of the bolt in the barrel and in the slot m to permit rotation through a quarter-turn and to hold the foot-piece up off the floor when the lock is not in use. When the handle is thrown out at right angles to the door, the bolt is turned a quarter, the pin n' traveling in the slot m , and the foot-piece is correspondingly turned out from

ments, what I claim, and desire to secure by Letters Patent, is—

1. In a structure of the class described the combination with a rotatable upright of a series of doors mounted upon the upright and extended at angles to each other, the lines of both sides of all the angles between the doors being eccentric to the axis of rotation, and a casement having arc-shaped sides concentric to the axis of rotation as and for the purpose specified.
2. In a structure of the class described the combination with a rotatable upright of a series of doors extended at angles to each other the lines of both sides of all the angles being eccentric to the axis of rotation, one or more of said doors being connected permanently to the upright and the others being hinged to those permanently connected so as to fold together as specified.
3. In a structure of the class described the combination with a rotatable upright of a series of doors extended at angles to each other the lines of both sides of all the angles being eccentric to the axis of rotation, one or more of said doors being permanently connected to the upright and the others being hinged to those permanently connected, and mechanism for locking the hinge connections as specified.
4. In a structure of the class described, the combination with the upright and the doors permanently connected and hinged thereto, of a hinged locking mechanism comprising a piece D having a hinged member d provided with a lever-actuated, swiveling, eccentric cam, and a striking-piece D' provided with a catch d³ as specified.
5. In a structure of the class described, the combination with the upright and the casement-floor, of the plates provided with the ball-race, and the elastic dust-shield secured to the bottom of the upright and adapted to bear upon the floor around said plates as specified.
6. In a structure of the class described the combination with the upright provided with folding doors and sliding pivot-pins, of parallel slideways formed in the ceiling of the casement and contractible and extensible suspending means foldably connected with two of the doors on opposite sides of the upright and adapted to engage and disengage with the slideways as specified.
7. In a structure of the class described, the combination with the casement, doors and

pivoted upright, of the suspending means comprising parallel slideways in the ceiling of the casement, a sliding piece fitted to slide in each of the ways, and a pair of threaded bolts 60 for each of the slideways connected by a threaded sleeve, one of said bolts being pivoted to the door and the other of the bolts being provided with a T-head, adapted to engage the sliding piece as specified. 65

8. In a structure of the class described the combination with a rotatable upright of a series of wedge-shaped doors having their thickest portion adjacent to the upright, the doors being extended on lines substantially parallel with and clear off from a center line so as to afford free space between the thickest part of the doors and such center line as specified. 70

9. In a structure of the class specified, the combination with the upright of the doors 75 made in two parts and connected by a hinge-joint at one side and a spring on the opposite side adapted to hold the joint closed in normal use and to yield and permit flexion of the door under unusual resistance as specified. 80

10. In a structure of the class specified the door A made in two parts in combination with a hinge h on one side and a jointed rod I 85 spring I' and pivoted stud i² as specified.

11. In a structure of the class specified, the combination with the revolving structure and casement of a locking means comprising a bolt provided with an elastic foot-piece, with a curved bottom pivoted to the bolt eccentrically to the curve of the bottom and lever mechanism for actuating the bolt in pressing the foot-piece upon the floor of the casement at any point of its path thereon as specified. 90

12. In a structure of the class specified, the 95 combination with the revolving structure and casement of a locking means comprising a plate provided with screw-holes and inclined teeth, a barrel mounted on the plate, a bolt fitted to slide in the barrel and provided with 100 stops limiting its rotation to a quarter-turn, an elastic foot-piece eccentrically pivoted to the lower end of the bolt and a lever mounted to revolve a quarter-turn on the bolt and provided with inclined teeth adapted to engage the inclined teeth of the plate on the 105 quarter-turn as specified.
